UNITED STATES PATENT OFFICE.

JAMES M. SINCLAIR, OF NEW YORK, N. Y.

PARTITION-WALL.

SPECIFICATION forming part of Letters Patent No. 416,428, dated December 3, 1889.

Application filed July 20, 1889. Serial No. 318,168. (No model.)

To all whom it may concern:

Be it known that I, JAMES M. SINCLAIR, of New York city, in the county and State of New York, have invented a new and useful Improvement in Partition-Walls, of which the following is a full, clear, and exact description.

My invention relates to an improvement in partition-walls, and has for its object to provide a means whereby a partition-wall—fire-proof, if desired—may be conveniently and expeditiously erected in any room, and quickly and easily removed without injury to the side walls or to the ceiling.

The invention consists in the novel construction and combination of the several parts, as will be hereinafter fully set forth, and pointed out in the claims.

Reference is to be had to the accompanying drawings, forming a part of this specification, in which similar letters and figures of reference indicate corresponding parts in all the views.

Figure 1 is a partial interior view of a room divided into sub-compartments by my improved partition. Fig. 2 is a perspective view of a panel employed in connection with the partition. Fig. 3 is a central vertical section taken between two opposed standards of the partition, the panels upon one side being removed. Fig. 4 is a perspective view of a portion of the partition. Fig. 5 is a perspective view of one of the tie or panel bars. Fig. 5^a is a partial perspective view of the inner side of one of the face-plates. Fig. 6 is a transverse section on line 6 6 of Fig. 3, with the panels removed. Fig. 7 is a partial front elevation of the partition when ornamental panels are employed. Fig. 8 is a section taken on line 8 8 of Figs. 7 and 9, and Fig. 9 is a section on line 9 9 of Figs. 7 and 8.

In carrying out the invention the uprights or standards A of the partition consist of two pairs 10 and 11 of angle-irons placed face to face a suitable distance apart, the irons of each pair being so placed that the longitudinal edges of one of their members will constitute the outer faces, and the sides of the other members the inner faces, as best shown in Figs. 4 and 6. Each pair of angle-irons is connected by a series of transverse T-irons

or braces 12, preferably arranged at intervals apart corresponding to the height of the panels to be employed in the construction of the partition. The horizontal members of the T-irons are placed uppermost, whereby a flat bearing-surface a is obtained between the opposed pairs of angle-irons forming the standards, and the upper horizontal members of the T-irons are sufficiently cut away to permit the extremities of the webs or vertical members to pass between the opposed outer members of each pair of angle-irons, as shown in Fig. 6, the T irons or braces being secured to the angle-irons by suitable screw-bolts or rivets. These standards or uprights A may be constructed in a shop, the height of the ceiling being known, and carried in a convenient state to the building in which the partitions are to be erected.

When the standards have been placed in position at suitable intervals apart, a longitudinal base strip or strips 13 are secured to the upper or bearing surfaces of the lower T irons or braces 12, as shown in Figs. 3 and 4, and a series of panel or tie bars 14, T-shaped in cross-section, are introduced between the several uprights, the ends being made to rest upon the T irons or braces 12 of the standards.

One of the tie or panel bars is illustrated in detail in Fig. 5, from which it will be observed that a longitudinal slot 15 is cut in each extremity of the web-section b, which constitutes the horizontal member, and a transverse recess 16 is produced in the extremities of the head-section b', constituting the vertical member. When the panel or tie bars are placed in position, their ends rest upon the brace-bars 12 of the standards A, as aforesaid. The inner members of the angled irons of the standards enter the slots 15, and that portion of the extremities in advance of the slots bears snugly against the side faces of the outer members of the standard angle-irons, as illustrated at d in Figs. 4 and 6, the base-wall of the recesses 16 being in a plane with the outer face of the standards.

In connection with the frame above described, I employ panels 17, which may be constructed of any desired material having a plain or an ornamental outer face, which

panels, as shown in Fig. 2, are provided upon the outer face with a marginal rabbet 18, the rabbet at the sides being deeper than that at the ends, and in the rabbeted end surfaces a transverse groove 19 is formed. These panels are placed in position in the following manner: The lower panel or tie bar 14 is seated between two of the standards A, and a panel is introduced between the standards 10 and slid down until the rabbeted lower side edge is passed to the rear of the outer member b' of the tie-bar, and said edge rests upon the horizontal or shank member b of the same, whereupon the upper wall of the lower rabbet contacts with the upper edge of the member b' of the said tie-bar, as shown in Fig. 3, and, as the rabbet is of a depth equal to the thickness of the member b', the outer face of said member and the outer face of the 20 panel will be flush. The width of the panels is such that they contact with the opposed side faces of the outer members of the standard angle-irons. The next tie-bar is now placed in position and the upper rabbeted 25 edge of the panel clamped thereon, and this operation is repeated until all the panels have been placed in position, the ceiling and cornice forming a tie-plate for the upper edge of the upper panels. It is now necessary to tie 30 the ends of the panels to place, and this is accomplished through the medium of a perpendicular face-plate 20, a portion of which is illustrated in detail in Fig. 5^a. The face-plate is of a width equal to the space intervening 35 between the opposed walls of the recesses 16 in the horizontally-aligning tie-bars 14, and said plate is provided with an inner flange 21 upon the sides, which flanges are provided with recesses 22, spaced to correspond 40 with the distance between the vertical series of panel or tie bars. The perpendicular face-plates are made to cover the outer side edges of the several pairs of standard angle-irons, the flanges 21 entering the grooves 45 19 of the panels, and the recessed portions 22 the recessed surfaces 16 of the panel or tie bars, and the face-plate of each standard is connected and held in position by screw-bolts 24, which pass from one face of the partition to the other between the several pairs 50 of angle-irons 10 and 11, as best shown in Figs. 4 and 6. When the partition has been completed, as above described, the outer face is perfectly smooth if plain panels are employed, as shown in Fig. 1, which clearly illustrates the application of the partition to a 55 large room, whereby it is subdivided.

In Figs. 7, 8, and 9, I have illustrated a slightly-modified construction, especially 60 adapted for use in connection with ornamental panels. The departure consists, principally, in the formation of the standards and face-plates. The standards are composed of a single metal beam, substantially of girder 65 shape, as shown at 25 in Fig. 9, the said standards having integral with their front and rear faces a longitudinal rib 26, and

plates 27 secured to the side faces to support the panel tie-bars, which plates 27 correspond with the T-braces 12. The recesses 16 in the 70 panel or tie bars 14 are made to extend farther back than shown in Fig. 5, and the outer face is ornamental. The face-plates are made in sections—namely, a series of straight sections D and cross-shaped sections D', the 75 cross-shaped sections D' being located where the corners of the panels approach, as shown in Fig. 7, and the straight sections in contact with and above and below the top and bottom members of the cross. The face-plates 80 are secured to the ribs 26 of the standards by means of screws 28 or equivalent fastening devices.

Having thus described my invention, I claim as new and desire to secure by Letters Patent— 85

1. In a portable partition, the combination, with standards provided with attached transverse bearing-bars at intervals in their length, of transverse tie or panel bars essentially T-shaped in cross-section, contacting with 90 the several standards and supported by the said bearing-bars, substantially as shown and described, whereby a series of spaces is formed for the reception of the panels, substantially as shown and described. 95

2. In a portable partition, the combination, with a series of standards and horizontal bearing-bars secured to the standards at intervals in their length, of a series of panel or tie bars contacting with the standards and supported by the said bearing-bars, which tie or panel bars are essentially T-shaped in cross-section, and perpendicular face-plates secured to the faces of the standards, which face-plates are rabbeted in the extremities of 105 the tie or panel bars, substantially as shown and described.

3. In a portable partition, the combination, with perpendicular standards comprising pairs of angle-irons united by essentially T-shaped bearing-bars, of a series of panel or tie bars T-shaped in cross-section, provided with transverse recesses in the outer face at the extremities, which tie or panel bars are supported by the said connecting-bars, and perpendicular face-plates secured to the outer faces of the standards and filling the recesses in the tie or panel bars, substantially as 110 shown and described, whereby the outer faces of the partition are straight and smooth, 115 as specified. 120

4. In a portable partition, the combination, with a series of standards comprising pairs of angle-irons, and essentially T-shaped bearing-bars uniting the opposed pairs of angle-irons and arranged at intervals in the length 125 of said angle-irons, of a series of transverse tie or panel bars T-shaped in cross-section, provided with a slot in the extremities of the horizontal member, and having each extremity of the vertical member provided with a transverse recess, and face-plates provided 130 with side flanges recessed at intervals, the said face-plates being secured to the outer

edges of the standards and covering the recesses in the tie or panel bars, substantially as shown and described.

5. In a portable partition, the combination, with a series of standards comprising pairs of angle-irons, and essentially T-shaped bearing-bars uniting the opposed pairs of angle-irons and arranged at intervals in the length of said angle-irons, of a series of transverse tie or panel bars T-shaped in cross-section, provided with a slot in the extremities of the horizontal member, and having each extremity of the vertical member provided

with a transverse recess, face-plates provided with side flanges recessed at intervals, the said face-plates being secured to the outer edges of the standards, covering the recesses in the tie or panel bars, and panels having a marginal rabbet securely held between the opposed standards, tie-plates, and face-plates, substantially as and for the purpose specified. 15 20
